CLAIM

The ornamental design for a gaming system combined light candle and indicator for a shared symbol display, as shown and described.

DESCRIPTION

This application relates to the following co-pending commonly owned patent applications: “Gaming System Combined Shared Symbol Display and Protective Dome,” Ser. No. 29/253,516, “Gaming System Dome for a Shared Symbol Display,” Ser. No. 29/253,510, “Gaming System Having a Combined Dome for a Shared Symbol Display Device,” Ser. No. 29/253,514, “Gaming System Dome Cap for a Shared Symbol Display,” Ser. No. 29/253,518, “Gaming System Dome Cap for a Shared Symbol Display,” Ser. No. 29/253,561, “Gaming System Display,” Ser. No. 29/253,508, “Gaming System Having a Combined Gaming Machine Display and Spacer Displays for a Shared Symbol Display,” Ser. No. 29/253,560, “Gaming System Indicator for a Shared Symbol Display,” Ser. No. 29/253,511, “Gaming System Light Candle,” Ser. No. 29/253,512, “Gaming System Light Candle,” Ser. No. 29/253,517, and “Gaming System Spacer Assembly for a Shared Symbol Display,” Ser. No. 29/253,515; and “Gaming System Having a Shared Symbol Display,” Ser. No. 29/247, 063.

FIG. 1 is a front perspective view of a gaming system combined light candle and indicator for a shared symbol display of our new design, that portion shown in phantom is not part of the design sought to be patented and is provided for environmental purposes only.

FIG. 2 is an elevated front view of the gaming system combined light candle and indicator for a shared symbol display of our new design illustrated in FIG. 1, that portion shown in phantom is not part of the design sought to be patented and is provided for environmental purposes only. FIG. 3 is an elevated back view of the gaming system combined light candle and indicator for a shared symbol display of our new design illustrated in FIG. 1, that portion shown in phantom is not part of the design sought to be patented and is provided for environmental purposes only. FIG. 4 is an elevated left side view of the gaming system combined light candle and indicator for a shared symbol display of our new design illustrated in FIG. 1, the right side being a mirror image thereof, that portion shown in phantom is not part of the design sought to be patented and is provided for environmental purposes only.

FIG. 5 is a top plan view of the gaming system combined light candle and indicator for a shared symbol display of our new design illustrated in FIG. 1, that portion shown in phantom is not part of the design sought to be patented and is provided for environmental purposes only.

FIG. 6 is an enlarged front perspective view of a gaming system combined light candle and indicator for a shared symbol display of our new design.

FIG. 7 is a top plan view of the gaming system combined light candle and indicator for a shared symbol display of our new design illustrated in FIG. 6.

FIG. 8 is an elevated left side view of the gaming system combined light candle and indicator for a shared symbol display of our new design illustrated in FIG. 6, the right side being a mirror image thereof.

FIG. 9 is an elevated front view of the gaming system combined light candle and indicator for a shared symbol display of our new design illustrated in FIG. 6; and,

FIG. 10 is an elevated back view of the gaming system combined light candle and indicator for a shared symbol display of our new design illustrated in FIG. 6.
